AREA LIGHT FIXTURE

Hyman Phillips, Cincinnati, Ohio, assignor to Oscar Phillips Co., Cincinnati, Ohio, a corporation of Ohio

Application March 31, 1955, Serial No. 35,305

Term of patent 7 years

(Cl. D48—23)

FIG. 2.

FIG. 1.

FIG. 3.

FIG. 4.

The distinctive feature of the design resides in the configuration of the end pieces of the fixture.

I claim:

The ornamental design for an area light fixture, as shown and described.
